H. R. PATTERSON

IGNITION DEVICE FOR AUTOMOBILES

Original Filed July 9, 1917

UNITED STATES PATENT OFFICE.

HARRY R. PATTERSON, OF TOLEDO, OHIO.

IGNITION DEVICE FOR AUTOMOBILES.

Application filed July 9, 1917, Serial No. 179,430. Renewed April 5, 1923.

To all whom it may concern:

Be it known that I, HARRY R. PATTERSON, a citizen of the United States, residing at Toledo, in the county of Lucas and State of Ohio, have invented certain new and useful Improvements in Ignition Devices for Automobiles, of which I declare the following to be a full, clear, and exact description.

This invention relates to improvements in ignition devices for internal combustion engines, and particularly to an improved condenser arrangement for use in the ignition circuit and improved connections between the condenser and the ignition circuit.

It is well known that it is highly desirable to connect a condenser in the primary ignition circuit, one of the objects of connecting a condenser in said circuit being to prevent sparking of the interrupter contacts. When a single condenser is thus connected in the circuit it is usually designed to have a capacity best suited to the average engine speed, or rather to the average frequency of circuit interruption. However, the desirable capacity of the condenser varies with the engine speed, so that, when the engine speed is high or, rather, the interval between the breaks of the circuit is less, a small capacity condenser is more desirable, and, when the engine speed is lower, a condenser of larger capacity is more desirable.

An object of my invention is to provide means for varying the capacity of the condenser connected in the primary ignition circuit, said means being controllable by the means for advancing and retarding the spark, and a further object is to provide for automatically connecting the ignition circuit to a condenser of smaller capacity when operating the engine at high speed and to a condenser of larger capacity when operating at low speed.

Further objects of this invention relate to economies of manufacture and details of construction as will hereinafter appear from the detailed description to follow. I accomplish the objects of my invention in one instance by the devices and means described in the following specification, but it is evident that the same may be varied widely without departing from the scope of the invention as pointed out in the appended claims. A structure constituting one embodiment of my invention, which may be the

preferred, is illustrated in the accompanying drawings forming a part thereof, in which:

Figure I is a view in side elevation of a structure embodying my invention.

Figure II is a top plan view of the structure shown in Figure I, with the distributor cap removed.

Figure III is a vertical sectional view, taken substantially on the line III-III of Figure II.

Figure IV is an enlarged, detail, fragmentary, sectional view, taken substantially on the line IV-IV of Figure II, and

Figure V is a wiring diagram.

In the drawings, similar reference numerals refer to similar parts throughout the several views, and the sectional views are taken looking in the direction of the arrows at the ends of the section lines.

Considering the numbered parts of the drawing, I have shown an ignition device comprising the casing 10, having the removable distributor cap 11 carrying the central contact 12 and the contacts 13 near the edge. In the casing there is formed an interrupter chamber 14, and a condenser chamber 15. The shaft 16 is journaled in the casing 10 and carries the cam 17, which is adjustable relative to said shaft, and has a cylindrical stem 18 on which the distributor arm 19 is removably mounted, said distributor arm being adapted to successively sweep past the contacts 13 as the shaft 16 revolves.

The interrupter plate 20 is rotatably mounted in the bottom of the interrupter chamber 14, being journaled on a boss 21 formed in the bottom of said casing, and said interrupter plate 20 carries the pin 22 on which the interrupter lever 23 is fulcrumed. Said interrupter lever carries a contact 24, which is adapted to coact with the fixed contact 25, carried by the bracket 28, which is secured to the interrupter plate 20, but insulated therefrom by means of the insulating material 29. The bracket 28, and consequently the fixed contact 25, is connected in the primary ignition circuit by means of the lead wire 26 connected to the terminal 30, said terminal extending through a slot 27 formed in the bottom of the casing, so that it may move with the interrupter plate relative to the casing. Said terminal 30 has an upwardly extending stem 31

through which a connection is made, between the condenser and the primary ignition circuit.

Suitable movement is imparted to the interrupter plate 20 within the casing by means of the lever 32, which is fulcrumed on the pin 33, carried by the casing 10, and which lever carries a pin 34 extending through a suitable slot in the bottom of the casing and engaging the interrupter plate 20. A limited relative movement thus given to the plate 20 advances or retards the spark by moving the interrupter lever relative to the cam 17, in a manner which is well understood in the art.

In the condenser chamber 15, I provide a two-part condenser 35. Each part of said condenser is provided with a separate terminal, 36 and 37, through which they are connected with the primary ignition circuit. An arm 38 extends from the terminal 36 through a notch in the edge of the partition wall separating the condenser chamber from the interrupter chamber, and a similar arm 40 is connected with the terminal 37 and extends through said notch, said arms being supported from the side of the casing 10 by the screw 41, but insulated therefrom and from each other by means of the block 39 of insulating material. The arm 38 has connected thereto the long arm 42, as shown in Figure IV of the drawing, and the arm 40 has connected thereto the short arm 43, both of these arms and their relative position being illustrated in Figure IV. It will be seen that, as the interrupter plate 20 is moved to advance or retard the spark, the stem 31 which is adapted to contact with the arms 42 and 43 will be moved relative to them, so that, in one position, it will contact with both the arm 42 and the arm 43, while, in another position it will contact only with the arm 42.

According to the wiring diagram illustrated by Fig. V, the primary circuit may include a battery 46 in series with the primary winding 44 of the induction coil and the stationary and movable contacts 25 and 24 of the interrupter, the two ends of the circuit being grounded as at 45 and 47. The secondary winding may be connected at one end to the primary and have its opposite end connected with the central contact 12 of the distributor, the contacts 13 of which connect with the spark plugs and thence with the ground 50. The two-part or variable condenser 35, having one side grounded as at 48, has its two parts connected by the terminals 36 and 37 and by the arms 42 and 43 to the primary circuit, the connection being effected by the stem 31 to include one or both parts of the condenser in accordance with the position of the interrupter plate.

From the description of the parts given above, the operation of my device should be very readily understood. When the engine

is operating at low speed, and the spark is consequently retarded, the interrupter plate 20 will be in such a position that the stem 31 of the contact 30 will engage both the arms 42 and 43, so that both parts of the condenser 35 are connected to the primary circuit. As the interrupter plate 20 is rotated by means of the lever 32 in a counter-clockwise direction as viewed in Fig. II, so as to move the interrupter lever relative to the cam and advance the spark, the terminal 30 carrying the stem 31 will move with the plate relative to the arms 42 and 43, until it breaks connection with the short arm 43 thereby cutting out that part of the condenser which is connected thereto. As a result, it will be seen that, when the engine speed is low, and a high capacity condenser is desirable, both parts of the condenser are connected in the ignition circuit, so as to best meet the conditions prevailing at that time. However, as the spark is advanced and the engine speed is increased, a part of the condenser will automatically be cut out of the circuit, so that, when the engine speed is high, the capacity of the condenser will be lower and the conditions maintaining at that time will be best met.

I am aware that the particular embodiment of my invention here shown and described is capable of considerable variation, without departing from the spirit of my invention, but I have found that this particular embodiment is desirable from many standpoints, and, therefore, I desire to claim the same specifically as well as broadly, as indicated by the appended claims.

Having thus described my invention, what I claim as new and desire to secure by Letters Patent is:

1. In a device of the class described, the combination of a casing, having an interrupter chamber and a condenser chamber; an interrupter plate rotatably mounted in said interrupter chamber; a bracket mounted on said plate, but insulated therefrom; a fixed contact carried by said bracket; an interrupter lever mounted on said plate; an interrupter cam adapted to vibrate said lever; means for rotating said plate to advance and retard the spark, said interrupter lever carrying a contact adapted to coat with said fixed contact to open and close the primary ignition circuit; a plurality of condensers carried in said condenser chamber; a contact arm connected to each condenser, said contact arms being of varying length, and insulated from each other; and a terminal carried by said interrupter plate and electrically connecting said bracket with a source of current, and having an upwardly extending stem adapted to engage one or more of said contact arms according to the position of said plate.

2. In a device of the class described, the

- combination of a casing, having an interrupter chamber, and a condenser chamber; an interrupter plate rotatably mounted in said interrupter chamber; a bracket mounted on said plate, but insulated therefrom; a fixed contact carried by said bracket; a vibratory interrupter lever mounted on said plate and carrying a contact adapted to coact with 5 said fixed contact; means for vibrating said lever; means for rotating said plate to advance and retard the spark; a plurality of condensers carried in said condenser chamber; a contact arm connected to each condenser, said contact arm being of varying length and insulated from each other; and means, carried by said interrupter plate, electrically connecting said fixed contact with a source of current, and comprising an 10 upwardly extending stem adapted to engage one or more of said contact arms according to the position of said plate, so as to connect one or more of said condensers in said primary ignition circuit.
- 25 3. In a device of the class described, the combination of a casing having an interrupter chamber and a condenser chamber; and an interrupter plate rotatably mounted in said interrupter chamber; interrupter mechanism carried by said plate; means for moving said plate to advance and retard the spark; a plurality of condensers carried in said condenser chamber; a contact arm connected to each condenser, said contact arms being of varying length; and a terminal carried by said interrupter plate electrically connecting said interrupter mechanism with a source of current, and having an 30 upwardly extending stem, adapted to engage one or more of said contact arms according to the position of said plate.
- 40 4. In a device of the class described, the combination of a casing, having an interrupter chamber and a condenser chamber; a plate movable in said interrupter chamber; interrupter mechanism disposed in said chamber; means for moving said plate to advance or retard the spark; a plurality of condensers carried in said condenser chamber; a contact arm connected to each condenser, said contact arms being of varying length; and a terminal movable with 45 said plate and electrically connecting said interrupter mechanism with a source of current, and having an upwardly extending stem adapted to engage one or more of said contact arms, according to the position of said stem.
- 55 5. In a device of the class described, the combination of a casing, having an interrupter and a condenser chamber; an interrupter plate rotatably mounted in said interrupter chamber; a bracket mounted on said plate, but insulated therefrom; a fixed contact carried by said bracket; an inter- 60 rupter lever mounted on said plate; an interrupter cam adapted to vibrate said lever; means for rotating said plate to advance and retard the spark; a plurality of condensers carried in said condenser chamber; a contact arm connected to each condenser, said contact arms being of varying length; and means movable with said interrupter plate, and electrically connecting said bracket with a source of current, and adapted to electrically connect one or more of said contact arms with said source of current, according to the position of said plate.
- 65 6. In a device of the class described, the combination of a casing, having an interrupter chamber and a condenser chamber; an interrupter plate rotatably mounted in said interrupter chamber; a bracket mounted on said plate, but insulated therefrom; a fixed contact carried by said bracket; an interrupter lever mounted on said plate; an interrupter cam adapted to vibrate said lever; means for rotating said plate to advance or retard the spark; a plurality of condensers carried in said condenser chamber; and means movable with said interrupter plate, and electrically connecting said bracket with a source of current, and adapted to connect one or more of said condensers with said source of current, according to the position of said plate.
- 70 7. In a device of the class described, the combination of interrupter mechanism; timer means movable to time the spark; a plurality of condensers; a contact arm connected to each condenser, said contact arms being of varying lengths; and a terminal, carried by said timer means, electrically connecting said interrupter mechanism with a source of current, and adapted to connect one or more of said contact arms with said source of current, according to the position of said timer means.
- 75 8. In a device of the class described, the combination of an interrupter mechanism; timer means movable to time the spark; a plurality of condensers; and means electrically connecting said interrupter mechanism with a source of current and adapted to connect one or more of said condensers with said source of current, according to the position of said timer means.
- 80 9. In a device of the class described, the combination of a primary ignition circuit, comprising a source of current, a primary induction coil winding, an interrupter mechanism, and timer means for timing the make and break of said circuit, a condenser of variable capacity connected to said circuit, means connected with said timer means for varying the capacity of said condenser, and a secondary circuit comprising a secondary induction coil winding, and distributor mechanism connected in said secondary circuit.
- 85 100 105 110 115 120 125 126

10. In an ignition system, the combination of a primary circuit, comprising a source of current, interrupter mechanism, timer means for timing the make and break of said circuit, a primary induction winding and a condenser connected to said primary circuit, the capacity of said condenser being variable and controlled by said timer means; and a secondary circuit comprising 10 a distributor.
11. In an ignition system, the combination of a primary circuit, including means for making and breaking said circuit, means for timing the make and break of said circuit, a 15 condenser connected to said primary circuit, and means for simultaneously varying the capacity of said condenser and for actuating said timing means.
12. In an ignition system, the combination 20 of a primary ignition circuit; interrupter mechanism in said circuit for making and breaking the same; timer means for timing the make and break of said circuit; and means for connecting to said circuit one or 25 more sections of a variable condenser, said means being controlled by said timer means.
13. In an ignition system, the combination 30 of an ignition circuit; means for making and breaking said circuit; timer means for timing the make and break of said circuit; and a condenser of variable capacity connected in said circuit, and operatively related to said timer means.
14. In an ignition system for an internal 35 combustion engine, the combination of an ignition circuit, an engine driven interrupter for said ignition circuit, a variable condenser connected to said ignition circuit and means for simultaneously varying 40 the timing of said interrupter and varying the capacity of said condenser.
15. In an ignition system for an internal 45 combustion engine having an engine driven interrupter and a condenser connected thereto a single actuated member for simultaneously varying the relative time of operation of said interrupter and varying the capacity of the condenser.
16. In an ignition system for an internal 50 combustion engine including an induction coil, a condensate in circuit therewith and a circuit interrupter therefor operated by said engine, the combination of means for advancing the time of occurrence of the ignition spark in said engine and automatic 55 means for reducing the value of the condensate as the spark is advanced.
17. In an ignition system, the combination of an ignition circuit, engine actuated circuit controlling means for making and breaking said circuit, a variable condenser intercalated in said circuit, and means for advancing or retarding the breaking of said circuit relative to a fixed point in the engine cycle and concomitantly varying the 60 capacity of said condenser.
18. In an ignition system, the combination of an ignition circuit, engine actuated circuit controlling means for making and breaking said circuit, a variable condenser 65 intercalated in said circuit, and means for advancing or retarding the breaking of said circuit relative to a fixed point in the engine cycle and concomitantly reducing the condenser capacity when the breaking of 70 said circuit is advanced, and increasing the condenser capacity when the breaking of 75 said circuit is retarded.
19. In an ignition system, the combination of an ignition circuit; means for making and breaking said circuit; means for advancing and retarding the make and break of said circuit; a condenser; and means for connecting all of said condenser 80 to said circuit, when the make and break of said circuit is retarded, and for connecting a part only of said condenser to said circuit, when the make and break is advanced.
20. In an ignition system, the combination of an ignition circuit; means for making and breaking said circuit; means for advancing and retarding the make and break of said circuit; a condenser comprising a 85 plurality of units; and means for connecting one or more of said units to said circuit, said means being controlled by the means for advancing or retarding the make and break of the circuit.
- In testimony whereof I affix my signature.
- HARRY R. PATTERSON.
